CONTAINER

Anton Novotny, Detroit, Mich., assignor to Detroit Gray Iron Foundry Company, Detroit, Mich., a corporation of Michigan

Application October 6, 1933, Serial No. 692,409

9 Claims. (Cl. 220—39)

This invention relates to improvements in containers and refers more particularly to containers in which beverages such as beer and the like may be stored and shipped.

5 It is an object of the invention to provide a container which is relatively cheap and simple to manufacture, and which has a large neck opening so that when the cover, equipped with necessary fittings, is removed the interior of the

10 vessel may be easily and thoroughly cleansed; and to provide ready means for making a tight joint between the vessel and the cover.

Another object of the invention is to provide such a container wherein the filling aperture, 15 provided with a closure, is formed through the cover towards one side thereof; wherein means are provided centrally of the cover for attachment of a dome-like casing by which the entire upper face of the cover and the fittings and 20 closure thereon are enclosed; and to perforate the casing so that when the latter is in position the excise stamp covering the outlet valve is clearly visible.

A further object of the invention is to provide 25 a container wherein a retaining ring is secured around the container neck and has integral handles formed thereon; and wherein the ring is adapted to receive fastening means for holding the cover upon the container so that the fastening means cannot be removed until after the casing has been taken off.

With these and other objects and advantages in view which will become apparent as the specification proceeds, the invention is hereinafter 35 more fully described with the aid of the accompanying drawings, in which:

Figure 1 illustrates a plan view of the invention wherein the retaining ring is clearly shown, and 40 Figure 2 is a sectional elevation of the invention.

Figure 3 is a section on the line 3—3 of Figure 1.

Figure 4 is a view on the line 4—4 of Figure 1, showing a portion of the cover with the outlet valve mounted thereon and the operating key for 45 the latter about to be placed upon the valve stem.

Figure 5 is an enlarged section on the line 5—5 of Figure 1, and

Figure 6 is a plan view of the dome-like casing.

Referring to the drawings, 1 designates a vessel 50 consisting of a main body portion 2, a base 3, and an upper portion or neck 4. The lower extremity of the body portion 2 and the periphery of the base 3 are suitably secured to one another to form a tight joint; in the present instance 55 these parts are rolled together as shown at 5. The upper margin of the body portion 2 and the lower margin of the neck 4 are welded or otherwise suitably secured to one another as shown at 6.

A retaining ring 7 is mounted around the upper 60 portion of the neck 4 which is upwardly and in-

wardly inclined thereby forming a rest for the underside of the said ring. The upper margin of the neck 4 is outwardly flared, preferably rolled as shown at 8, to form a projection which bears upon the upper face of the retaining ring to hold it securely in position.

Resting upon the outwardly rolled portion 8 of the neck 4 is a packing ring 9, preferably made of rubber, which is housed in an annular groove 10 formed in the underside of a cover 11. Through the latter apertures 12 are provided for the passage of screws 13 which engage the tapped holes 14 formed in the retaining ring 7, and integral with the latter opposed outwardly projecting handles 15 are provided.

Through the cover 11, towards one side of the latter, an aperture 16 is formed around which an upwardly projecting annular flange 16a is provided of the size and shape to receive the filler arm of a filling machine. The flange 16a is externally threaded to receive a cap 17, and 18 denotes a plug or bung which may also be inserted in the aperture 16 under the said cap. Centrally of the upper face of the cover 11 a tapped hole 19 is provided to receive a screw 20 which depends 85 centrally from a dome-like casing 21 and is secured thereto. The casing has a plurality of apertures 21a formed therethrough for a purpose which will hereinafter become apparent. The lower peripheral margin of the casing engages an 90 annular recess 11a formed around the periphery of the cover 11 from its upper face for a portion of its depth. Thus when the casing is in position the upper face of the cover is completely enclosed. It will also be observed that the screws 13 cannot 95 be removed until after the casing has been taken off.

Mounted upon the cover 11 and towards one side thereof is a discharge valve 23. A tubular shank 23a integral with the body of the valve 100 projects through the cover 11 and is connected to an outlet pipe 24 which preferably extends substantially to the bottom of the vessel 1. Swivelly mounted on one side of the valve 23 is a draw-off pipe 25 which is normally positioned as 105 shown in Figures 1 and 2 when it may be completely covered by the casing 21. Due, however, to its swivelled mounting this pipe 25 may be turned to the positions indicated at 25a in Figure 1, when it projects beyond the cover 11 so that 110 the contents of the vessel may be readily discharged into another container.

The valve 23 has an upper plate 26 formed integral with its body, and substantially centrally of the width and length of this plate an opening 115 26a is formed in which the multi-sided upper extremity of a valve stem 27 terminates. When the vessel 1 is utilized as a container for beer or other beverage on which an excise stamp must be placed, this stamp, indicated at 28, is pasted upon 120

the plate 26 across the opening 26a. When the beverage is to be withdrawn a key 29 is pushed through the stamp to engage the valve stem 27 and turn the latter. Thus in order to draw the beverage from the container it is necessary to cancel the stamp.

The container 1 is preferably charged with gas when it is filled so that when the valve 23 is opened the beverage is forced out. 30 denotes a conventional inlet valve through which additional gas or compressed air may be injected, if needed, into the container for removal of the beverage. The key 29 is internally threaded at 29a to cooperate with the external thread on the inlet valve 30 so that it may be safely carried prior to its insertion upon the valve stem 27 and the cancellation of the stamp 28.

From the foregoing description it is thought that the invention will be readily understood. Briefly, the screws 13 by which the cover 11 is held upon the vessel cannot be removed until the casing 21 has been taken off. This casing with its screw 20 is centrally mounted upon the cover so that the fittings upon the upper face of the latter are protected during shipment, and at the same time the casing apertures 21a facilitate inspection of the stamp 28. The valve key 29 is mounted upon the inlet valve 30 during shipment and prior to opening the container, and the retaining ring 7 as well as receiving the screws by which the cover 11 is held in place also has handles 15 formed thereon. Due to the latter arrangement it will be seen that after removal of the cover 11 ease of handling the vessel during cleansing is also provided for.

While the preferred embodiment of the invention has been described and shown, it is understood that the construction is susceptible to such alterations and modifications as fall within the scope of the appended claims.

What I claim is:

1. In a container, a body portion having a top, a valve mounted upon said top, said valve provided with a valve operating member and a plate surrounding the same adapted to receive a puncturable seal extending completely over the valve operating member, and a dome-like casing surmounting the cover over the valve plate, said casing being releasably secured to the cover and having an aperture through which said valve plate is visible.

2. In a container, a body portion, a cover therefor having an axially disposed threaded connection on its upper face, a valve carried by the cover arranged at one side of the threaded connection, said valve adapted to have a breakable stamp secured thereover, a dome-like casing surmounting and enclosing the cover having an axially threaded connection adapted to cooperate with the threaded connection on the cover to secure the casing thereover, said casing provided with a series of apertures arranged circumferentially about its axis a distance corresponding to the distance the valve is offset from the axis of the cover.

3. In a container, a body portion, a cover thereon, a valve mounted upon the cover, a dome-like casing the lower extremity of which rests adjacent the peripheral margin of the cover, and threaded means arranged coaxially with the casing and housed entirely within the latter supporting the casing upon the cover so that by applying rotary pressure to the casing periphery said casing may be removed.

4. In a container, a body portion, a cover thereon, a valve mounted upon the cover, the valve being adapted to have a seal so secured thereon that it must be broken before the valve can be opened, and a dome-like casing rotatably connected with the cover and having its peripheral margin resting adjacent the periphery of the latter, said casing having a plurality of apertures formed therethrough so that the seal is visible therethrough at all rotary positions of the casing. 80

5. In a container, a body portion having an open neck, a cover thereon, an axially disposed threaded connection on the upper face of the cover, the latter being apertured at one side of the threaded connection to provide a filler inlet, a closure on the inlet, a dome-like casing extending over the cover and filler inlet, and a threaded connection arranged axially within the casing coaxing with the first named threaded connection so that the casing may be readily removed by applying rotary pressure to the casing with the hands. 85

6. A container comprising a body having an open neck, a retaining ring secured around said neck beneath its upper margin, a cover resting upon said upper margin, means holding the cover upon the neck, said means engaging said ring, an axially disposed threaded connection on the upper face of the cover, the latter being apertured, a closure on said aperture, a valve extending through the cover, an outlet pipe in the container extending downward from the valve, said closure and valve both being arranged radially outward from the threaded connection, a dome-like casing extending over the cover, valve, and closure, and an axially disposed threaded connection on the casing coaxing with the first named connection. 100

7. In a container, a body having a cover thereon, a dome-like casing over the latter, threaded means arranged coaxially with the cover and casing housed entirely within the latter supporting the casing, a discharge valve mounted upon the cover and spaced radially outward from said threaded means, an outlet pipe extending through the cover into the body of the valve, and a draw-off pipe pivoted on the valve which may be housed within the casing or turned pivotally when the casing is removed to project laterally beyond the cover. 115

8. In a container, a body portion having a top, a valve mounted upon said top, said valve provided with a valve operating member and a plate surrounding the same adapted to receive a puncturable seal extending completely over the valve operating member, and a casing carried by the container and extending upwardly therefrom around the valve to protect the seal upon the seal plate, said casing being apertured at the top to permit inspection of said seal. 120

9. In a container, a body portion having a top, a valve mounted upon said top, said valve provided with a valve operating member and a plate surrounding the same adapted to receive a puncturable seal extending completely over the valve operating member, and a casing carried by the container and extending upwardly therefrom to a height greater than any portion of the valve structure to protect the latter in its entirety, said casing being provided with an opening at the top to permit inspection of the plate upon the valve. 130

ANTON NOVOTNY.
